CLAIM

We claim the ornamental design for a jar with lid and label, as shown and described.

DESCRIPTION

FIG. 1 is a perspective view of a front, a top, and a left side of a jar with lid and label, in accordance with a first embodiment of the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a front, a bottom, and a left side thereof;

FIG. 9 is a perspective view of a front, a top, and a left side of a jar with lid and label, in accordance with a second embodiment of the design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a perspective view of a front, a bottom, and a left side thereof.

The broken lines shown in the drawings illustrate portions of the jar with lid and label and form no part of the claimed design.

The jar of the jar with lid and label is entirely transparent, and the oblique line shading shown in the drawings illustrate the transparency of surfaces of the jar.
